JAMES M. CLARK, 3d, OF ATTLEBORO, MASSACHUSETTS, ASSIGNOR OF ONE-THIRD TO THOMAS F. WILLIAMS, OF ATTLEBORO, MASSACHUSETTS.

TARGET-PRACTICE ATTACHMENT FOR FIREARMS

No. 882,551.

Specification of Letters Patent. Patented March 24, 1908.

Application filed September 8, 1906. Serial No. 333,823.

To all whom it may concern:

Be it known that I, JAMES M. CLARK, 3d, a citizen of the United States, residing at Attleboro, in the county of Bristol and State of Massachusetts, have invented a new and useful Improvement in Target-Practice Attachments for Firearms, of which the following is a specification.

This invention has reference to an improvement in target practice attachments for small firearms, such as rifles, carbines or muskets.

Target practice with small firearms as heretofore accomplished required the use of an outdoor or indoor range of considerable length and also the use of regulation or special cartridges. The first of these requirements is sometimes prohibitive and the use of cartridges is expensive and at times, or in certain places, objectionable on account of the resultant noise from the use of the same.

The object of my invention is to improve the construction of a target practice attachment for rifles, carbines, muskets or similar firearms whereby the use in target practice of a regular range and ammunition with the resulting expense and noise is eliminated.

A further object of my invention is to construct the attachment and target in such proportions that the target at a short distance from the muzzle of the gun will appear to the eye the same size as a regulation target would appear at a certain distance usually required in target shooting.

My invention consists in the peculiar and novel construction of a target practice attachment for firearms, such as rifles, carbines or muskets, said attachment being adapted for use in the barrel of the firearm, actuated by the firing bolt or hammers of the gun and having details of construction, as will be more fully set forth hereinafter and claimed.

Figure 1 is a side view partly in section of a repeating rifle provided with my improved target practice attachment. Fig. 2 is a side view of the attachment removed from the rifle. Fig. 3 is an enlarged detail sectional view taken lengthwise through the breech end of the attachment. Fig. 4 is an enlarged detail sectional view taken lengthwise through the muzzle end of the attachment, and Fig. 5 is a face view of a target used in connection with the attachment.

In the drawings, *a* indicates a rifle of the

take-down pattern, *b* my improved target practice attachment, and *c* a target used in conjunction with the attachment *b*. The rifle *a* has the usual barrel 6 in which is the bore 7 terminating at the breech end in the cartridge chamber 8, the fore sight 9, the rear sight 10, the firing bolt 11, and pin 12, trigger 13, and stock 14, as shown in Fig. 1. The target practice attachment *b* consists of a cylindrical tube 15 approximately the length and diameter of and adapted to fit in the bore 7 and having the enlarged cartridge-shape breech end 16 with the annular lip 17 adapted to fit in the cartridge chamber 8, the internal bushing 18 with the central hole 19 adjacent the breech end 16, the internal stop bushing 20 having the central hole 21 adjacent the muzzle end 22, a light rod 23 extending the length of the tube 15 through the holes 19 and 21 in the bushings 18 and 20 and constructed to have a hardened pin 24 removably secured in the breech end of the rod, a fixed collar 25 on the rod centrally between the bushings 18 and 20, a screw-threaded muzzle end 26 to which is secured a cylindrical head 27 having a circular recess 28 in its outer end, a central needle 29 surrounded by a ring of soft rubber 30 secured in the recess 28 and extending slightly beyond the point of the needle 29 and a light coiled spring 31 on the rod 23, one end of which engages with the stop bushing 20 and the opposite end with the fixed collar 25 on the rod 23, as shown in Figs. 1, 3 and 4. The target *c* has the usual bull's eye 32 with the concentric rings 33 33 and an auxiliary bull's eye 34 placed on a vertical line above the bull's eye 32, as shown in Fig. 5, the distance between the bull's eyes 32 and 34 being equal to the distance from the center of the needle 29 to the point of the fore sight 9 from which the sight is taken, as shown in dotted lines in Fig. 1.

In the use of the attachment the gun is taken apart and the attachment inserted into the bore 7 of the barrel 6 through the breech end or cartridge chamber 8 and is held from being pushed through the barrel by the annular lip 17 on the breech end of the attachment, as shown in Fig. 1, and the gun assembled in the usual way. In rigid guns the attachment is inserted by removing the breech block. The target *c*, which may be of paper, is secured in the required position to a backing which may be faced with a

110

sheet of soft rubber to prevent injury to the needle 29. The shooter now takes the rifle in the usual way, draws back the bolt 11 and faces the target at a distance from the target which is such that by stretching out his arms the muzzle of the rifle will touch the target. The rifle is now drawn back into the usual firing position, with the butt against the shoulder, thus bringing the muzzle of the gun 10 six or eight inches from the target, the gun sighted at the upper bull's eye 34 on the target, and the trigger 13 pulled, which releasing the bolt 11 causes the firing pin 12 on the bolt to strike a blow on the pin 24 on the 15 end of the rod 25 and forces the rod out of the muzzle end of the barrel against the tension of the spring 31 and with sufficient force to cause the needle 29 to strike and pierce the target *c*, compressing the rubber spring 30, 20 which prevents injury to the target and expanding after the blow assists the coiled spring 31 in drawing the needle out of the target and returning the rod 23 to its normal position in the gun. If the aim of the shooter 25 is accurate at the bull's eye 34, the needle 29 will pierce the lower bull's eye 32.

By the use of my improved target practice attachment for rifles or similar fire arms, a regulation rifle may be quickly converted 30 into a rifle which may be used for target practice without the use of ammunition and as quickly converted back into a rifle in which ammunition may be used, without changing or altering the rifle in any way 35 whatsoever.

It is evident that the breech end of the rod 23 may be dished to receive the end of the firing pin 12, the target proportioned to correspond with fine or full sights or to correspond in size to the regulation targets as 40 they would appear to the eye at different distances, or the target could be used in a reverse position if desired without materially affecting the spirit of my invention.

Having thus described my invention, I 45 claim as new and desire to secure by Letters Patent;

1. In a fire arm, an automatic target practice attachment actuated by the firing mechanism of the fire arm and comprising a tube 50 adapted to be removably secured in the bore of the fire arm, a spring actuated rod in the tube, and means on the outer end of the rod for piercing a target when actuated by the firing mechanism.

2. In a fire arm, an automatic target practice attachment comprising a tube adapted to removably fit the bore and cartridge chamber of the fire arm, a rod in the tube adapted 60 to be thrown outward by the action of the firing mechanism of the fire arm, a coiled spring on the rod adapted to return the rod to its normal position, and means on the outer end of the rod for indenturing or piercing a target, whereby a fire arm may be used

for target practice without the use of ammunition.

3. In a fire arm, an automatic target practice attachment comprising a tube adapted to removably fit the bore and cartridge chamber 70 of the fire arm, a rod reciprocally supported in the tube and adapted to be thrown outward by the action of the firing mechanism of the fire arm, a coiled spring on the rod adapted to return the rod to its normal position, and a needle on the outer end of the rod adapted to pierce a target, whereby a fire arm may be used for target practice without the use of ammunition and without altering the firearm.

4. The combination with a fire arm of a target practice attachment *b* comprising a cylindrical tube 15 adapted to fit in the bore of the fire arm and having an enlarged breech end 16 with the annular lip 17 adapted to fit in the cartridge chamber of the fire arm, the internal fixed bushings 18 and 20 with the central holes 19 and 21, a light rod 23 extending in the tube through the holes in the bushings and constructed to have a hardened pin 24 removably secured in the breech end of the rod, a fixed collar 25 on the rod, a screw-threaded muzzle end 26, a cylindrical head 27 on the end 26, and having a circular recess 28 in the outer end, a central needle 29 in the recess 28, a ring of soft rubber 30 in the recess surrounding the needle 29 and extending slightly beyond the point of the needle, and a coiled spring 31 on the rod 23 one end of which engages with the fixed bushing 20 90 and the opposite end with the collar 25 on the rod 23, as described.

5. In attachments for small arms, the combination with a rigid rod adapted to be slidably mounted in the bore of a gun in the path of the firing pin and provided with a target marking point at its end opposite the firing pin, of a spring adapted to yieldingly resist forward movement of the rod.

6. The combination with a rigid rod adapted to be slidably mounted in the bore of a gun in the path of the firing pin and provided with a target marking point at the muzzle of the gun and with guide blocks fitting the interior of the barrel, of a stop to be detachably fixed to the barrel, a stop borne by the rod, and a spring to act between said stops and hold the rod in its rearmost position.

7. The combination with a gun, of a pointed rod slidably mounted in its bore in the path of the firing pin, and a spring yieldingly resisting the advance of the rod under the impact of the firing pin.

In testimony whereof I have signed my name to this specification in the presence of 125 two subscribing witnesses.

JAMES M. CLARK, 3RD.
